Primary Examiner — Vy N Koenig(74) *Attorney, Agent, or Firm* — The Weintraub Group, P.L.C.(57) **CLAIM**

The ornamental design for a seating frame, as shown and described.

DESCRIPTION

FIG. 1 is a perspective view of a seating frame showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Any shading and cross-hatching are not features of the design but are utilized to illustrate the surface contours of the seating frame design in the drawings.
